CLAIM

The ornamental design for a vehicle light, as shown and described.

DESCRIPTION

FIG. 1 is a top and front perspective view of a vehicle light showing our new design;

FIG. 2 is a front elevation thereof;

FIG. 3 is a rear elevation view thereof;

FIG. 4 is a right side elevation view thereof;

FIG. 5 is a left side elevation view thereof;

FIG. 6 is a top plan view thereof;

FIG. 7 is a bottom plan view thereof;

FIG. 8 is bottom and front perspective view thereof; and,

FIG. 9 is a top and rear perspective view thereof.

The broken lines in the figures illustrate portions of the vehicle light that form no part of the claimed design.

1 Claim, 9 Drawing Sheets
